Primary Examiner — Catherine Tuttle*(74) Attorney, Agent, or Firm* — Boyle Fredrickson S.C.**(57) CLAIM**

I claim the ornamental design for a soccer ball deflection panel, as shown and described.

DESCRIPTION

A portion of the disclosure of this patent document contains material that is subject to copyright protection. The copyright owner has no objection to the facsimile reproduction by anyone of the patent document or patent disclosure as it appears in the Patent and Trademark office, patent file or records, but otherwise reserves all copyright rights whatsoever.

FIG. 1 is a top side and front perspective view of the soccer ball deflection panel showing my new design;

FIG. 2 is a front elevational view thereof, the opposing view being identical thereto;

FIG. 3 is a side, top and rear perspective view thereof;

FIG. 4 is a side view thereof, the opposing side view being identical thereto;

FIG. 5 is a top view thereof, the opposing bottom view being identical thereto; and,

FIG. 6 is an enlarged scale right and left side view thereof. The soccer ball deflection panel forming part of the claimed design is a trademark of PROCONTROL™.
